(57) **CLAIM**

The ornamental design for a rooftop tent frame, as shown and described.

DESCRIPTION

FIG. 1 is a perspective view of a rooftop tent frame, showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the rooftop tent frame in an alternate closed configuration;

FIG. 10 is another perspective view of the rooftop tent frame in an alternate closed configuration;

FIG. 11 is an enlarged partial view of an area marked "11" in FIG. 1;

FIG. 12 is an enlarged partial view of an area marked "12" in FIG. 1;

FIG. 13 is an enlarged partial view of an area marked "13" in FIG. 1;

FIG. 14 is an enlarged partial view of an area marked "14" in FIG. 2;

FIG. 15 is an enlarged partial view of an area marked "15" in FIG. 2;

FIG. 16 is an enlarged partial view of an area marked "16" in FIG. 2;

FIG. 17 is an enlarged partial view of an area marked "17" in FIG. 9;

FIG. 18 is an enlarged partial view of an area marked "18" in FIG. 9; and,

FIG. 19 is an enlarged partial view of an area marked "19" in FIG. 10.

The broken line showing of buckles and straps are included for the purpose of illustrating portions of the rooftop tent frame that form no part of the claimed design.

1 Claim, 19 Drawing Sheets
